ATTORNEYS

UNITED STATES PATENT OFFICE.

HENRY CAVE, OF SPRINGFIELD, MASSACHUSETTS.

BRUSH OR THE LIKE.

Application filed March 7, 1923. Serial No. 623,556.

To all whom it may concern:

Be it known that I, HENRY CAVE, a citizen of the United States, residing at Springfield, in the county of Hampden and State 5 of Massachusetts, have invented new and useful Improvements in Brushes or the like, of which the following is a specification.

This invention relates to improvements in brushes, polishers or the like, and, more particularly, to combination articles of this general nature having two or more kinds of elements, which may be used for performing different classes of service.

The invention, while capable of general 15 application, finds one advantageous use as a floor brush and, for such use, two brushing elements are provided, one of which is much stiffer than the other and is designed for removing threads, or any other material 20 having a tendency to cling to a rug or carpet,—the other brushing element being intended for ordinary use.

The broad object of this invention is to provide a combination article of the general 25 class described with two or more kinds of elements and a mounting for them in a suitable frame so that either one thereof may be brought into position for action, when and as desired.

30 A further object of the invention is to provide an article of the class described, which has a handle or frame enabling it to be pushed or pulled over the floor, or any other surface, together with a mounting of 35 the elements in the handle or frame in such a manner that one element will be brought into position for service by a push or pull on the handle and so that the other element will be brought into service by a movement 40 of the handle in a reverse direction.

45 Other objects relate to improvements in the construction, arrangement and disposition of parts as will appear in the following description and the illustrative embodiment of the invention in the accompanying drawings, in which,—

Fig. 1 is a side elevational view showing a brush embodying the invention;

50 Fig. 2 is a fragmentary plan view thereof, the brush being indicated merely in conventional form; and

Fig. 3 is a fragmentary view taken similarly to Fig. 1 and showing the brushing elements reversed.

55 Referring to these drawings; the invention is shown as embodied in a brush, suit-

able for household use and intended to be pushed or pulled over the floor. For this particular embodiment, the combination article referred to is a double brush, or a 60 brush with dual brushing elements, one of which is somewhat stiffer than the other, or is otherwise differently constituted, to enable it to perform a different class of work. As shown, the brush comprises bristles 1 65 which are secured to a core 2, such as a twisted wire core,—the bristles being secured in place between the twisted wires. As a simple expedient for obtaining dual brushing elements with one core and one 70 set of bristles, the periphery of the brush is made eccentric to the core. This may be done in any suitable way, as by trimming the bristles after the brush has been made up or by arranging the bristles during the 75 process of making the brush. The result, in any event, is the production of dual brushing elements, consisting of a group of relatively long bristles *b* and a group of shorter and therefore stiffer bristles *b'*. 80

While the brush is used as an illustrative example, other articles of a more or less analogous nature may, obviously, be equally well used in its place. Also the dual brushing elements may be formed in 85 various other ways and do not necessarily need to be formed from the same set of bristles. The main essential is a combination article having at least two elements intended for different classes of work. 90

Such an article, whatever its character, is mounted in a suitable frame in such a manner that any element can be brought into play, when desired. Preferably, also this object is accomplished with a minimum of 95 effort on the part of the operator and desirably is accomplished automatically on a reverse movement of the frame. As shown, the brush is pivotally mounted in a suitable frame 5, which may be substantially fork-shaped and this frame is provided with any suitable sort of handle, such as the handle 8, centrally disposed thereon. As a simple expedient, the two wires of the twisted wire core 2 are separated at each end of 100 the core and one of the wires, as 3, is used for the shaft or pivot, for the brush,—passing through an opening in a side arm of frame 5. The other wire, as 4, is disposed outside the side arm in such a way that it 105 is free to swing through a substantial angle, such as an angle of 180 degrees. This wire

4 coacts with lugs 6 on frame 5 as stops to limit its swinging movement in one direction and shoulders 7 provided on frame 5 function as stops to limit the swinging movement of wire 4 in the other direction.

Various other expedients for mounting the dual elements to accomplish the purposes set forth will readily occur to those skilled in the art and the expedients described are given primarily as illustrative examples, although they are in a measure at present preferred.

In use, the brush is pushed or pulled over the floor by the handle 8. Assuming that the handle 8 is pushed in the direction illustrated in Fig. 1, the brush may turn in frame 5 until wire 4 abuts lugs 6. This causes the longer set of bristles b to be brought into position for service and this set of bristles is usually used for ordinary service. However, if threads, or any other material having a tendency to cling to the carpet or rug, are encountered, the movement of the brush is reversed. This reversal may be effected by pulling on handle 8 or by swinging the latter in a counterclockwise direction from the position shown in Fig. 1 to that shown in Fig. 3 and then pushing on the handle. In any event, such a reversal causes the brush to turn in the frame until wire 4 abuts stops 7, whereby the shorter and stiffer bristles b' are brought into position for service.

The invention has been disclosed herein,

in an embodiment at present preferred for 35 illustrative purposes, but the scope of the invention is defined by the appended claims rather than by the foregoing description.

What I claim is:

1. The combination with a frame, of a 40 substantially cylindrical brush, a core therefor disposed eccentrically of the brush and mounted for turning movement in said frame, and means for limiting the relative turning movement of said core and frame. 45

2. The combination with a frame, of a substantially cylindrical brush, a core therefor disposed eccentrically of the brush and comprising a pair of twisted wires which are separated at the ends of the core, one 50 of said wires being mounted for turning movement in said frame, the other wire cooperating with said frame as a stop for limiting the turning movement of the other wire in said frame. 55

3. In an article of the class described, companion cleaning elements constructed for somewhat different classes of service, a frame, a member rotatably mounted in said frame and carrying said elements, a stop movable with said member, and spaced stops provided on said frame and cooperating with the first named stop to limit the rotation of said member on the frame. 60

In testimony whereof I have affixed my signature.

HENRY CAVE.
